DESIGN.

C. SQUIRE,

NAME PLATE FOR AUTOMOBILES.

APPLICATION FILED JUNE 14, 1921.

59,386.

Patented Oct. 11, 1921.

Inventor
CLARK SQUIRE

By Attorney
Richard J. Cook

UNITED STATES PATENT OFFICE.

CLARK SQUIRE, OF PUYALLUP, WASHINGTON.

DESIGN FOR A NAME-PLATE FOR AUTOMOBILES.

59,386.

Specification for Design:

Patented Oct. 11, 1921.

Application filed June 14, 1921. Serial No. 477,554. Term of patent 7 years.

To all whom it may concern:

Be it known that I, CLARK SQUIRE, a citizen of the United States, residing at Puyallup, in the county of Pierce, State of Washington, have invented a new, original, and ornamental Design for a Name-Plate for Automobiles, of which the following is a specification, reference being had to the accompanying drawing, forming part thereof.

Figure 1 is a perspective view of a name

plate constructed according to the present invention.

Fig. 2 is an end view of the plate.

Fig. 3 is a front view of the same.

Fig. 4 is a top view of the plate.

I claim:

The ornamental design for a name plate for automobiles, as shown.

CLARK SQUIRE.
